UNITED STATES PATENT OFFICE.

CLAIR D. LAKE, OF BINGHAMTON, NEW YORK, ASSIGNOR TO INTERNATIONAL TIME RECORDING COMPANY OF NEW YORK, OF ENDICOTT, NEW YORK, A CORPORATION OF NEW YORK.

TIME RECORDER.

Application filed July 20, 1923. Serial No. 652,696.

This invention relates to improvements in time recorders and is more particularly directed to improvements in the individual workmen's time recorder shown, claimed and described in the copending application of T. J. Watson, Patent No. 1,481,574, granted January 22, 1924.

In the aforesaid recorder means are provided for taking a start and finish record from a time-controlled wheel after which the wheel is reset to zero by the operator. The advance of the wheel from zero is controlled by means of a magnet which in turn is time-controlled. In using this recorder there is the possibility that the time-controlled wheel will be stepped forward after resetting but before the taking of a new start record. Under these conditions an improper start record will be secured.

One object of the present invention is to provide means whereby the time-controlled wheel will be locked against advancing movement after resetting until after the succeeding start record has been taken.

Other objects of the present invention reside in the improvement of certain details of construction which will be more fully set forth in the accompanying specification and claims and shown in the drawings which disclose a preferred embodiment of the invention.

In the drawings—

Fig. 1 is a side view of the recorder.

Fig. 2 is a detail part sectional view taken substantially on line 2—2 of Fig. 1.

Figs. 3 and 4 are details showing the parts in moved position.

In more detail, the recorder comprises a suitable casing within which are rotatably mounted time and time value wheels 10, 11. Fixed to these wheels is aligning wheel 12 and a ratchet wheel 13. The escapement wheel 14 at its hub is free from ratchet wheel 13 and is controlled by the escapement 16 which in turn is controlled by magnet 17. The escapement wheel has pivoted thereon a pawl 18 which cooperates with the ratchet wheel 13 and is engaged therewith by means of a spring 20. The time wheels and ratchet and aligning wheel are normally advanced by a coil spring 15. The reset shaft 21 is fast to wheels 10 and 11 and to ratchet wheel 13 and aligning wheel 12 and is provided with a hexagonal or like end to receive the resetting wrench preferably formed as a part of the removable printing manual 22. Fixed to the aligning wheel is a reset to zero stop pin 23. Cooperating with this stop pin when the recorder is reset to zero is a dog 24 pivotally mounted on a shaft 25 and having a tail portion 26 (see Fig. 3) normally resting upon a bail 27 which is also pivoted on shaft 25. When the recorder is being restored to zero the operator applies the resetting wrench 22 to the end of the shaft 21 and turns the shaft and parts 12, 10, 11 and 13 connected therewith in a clockwise direction until pin 23 engages the notch in dog 24 which then snaps forward under the lower edge of the pin 23. During this resetting operation the pawl 18 clicks idly over the teeth of ratchet wheel 13. The escapement wheel 14 remains stationary during this operation and the coil spring 15 is wound up. At the time when the dog 24 has engaged under the lower edge of the pin 23 the pawl 18 will be disposed half-way between two ratchet teeth on wheel 13. If now the dog 24 be rocked anticlockwise, to the position shown in Fig. 3, the ratchet wheel 13 and the parts connected therewith will automatically make one half a step of advance under the influence of the coil spring 15. Such movement will not occur, however, until the dog 24 is retracted rearwardly. This retraction of the dog is effected by the taking of the start record in the following manner. The depression of manual 22 through hook 38 effects the operation of the printing hammer 28 in the usual manner. Pivotally connected to the frame which is rocked by the manual is a link 28 which is slotted at its end as shown at 29 to receive a pin 30 which is spring-connected by spring 31 to the end of the link 28. Upon the actuation of the printing manual spring 31 will draw forward on the pin 30, which pin is carried in the bail frame 27 thereby rocking the bail in a counter-clockwise direction and engaging the aligning dog 32 with the aligning wheel 12. The upward rocking of the bail 27 will cause the tail 26 of the dog 24 to be elevated thereby rocking the dog anticlockwise and releas-

ing the zero stop pin 23. The zero stop pin now moves forward to the position shown in Fig. 3. Also pivotally mounted on shaft 25 is a card abutment lever 33. This card abutment lever 33 is provided with a cam surface 34 which also is adapted to engage the edge of pin 23. With the parts in the starting position as shown in Fig. 1, and also in the position shown in Fig. 3, this card abutment 33 is in the full line position. After the stop pin 23 has moved forward to the dotted line position 23^a (Fig. 3) the card abutment lever 33 will be rocked to the dotted line position and change the elevation of the card stop. The card abutment lever 33 is also provided with a rearwardly extending portion 35 which coacts with an interlocking element 36 which is adapted to be disposed in the path of the stop pin 37 on the hook member 38 as shown in Fig. 4. This part of the mechanism is similar to that shown in the application previously referred to and serves to prevent further printing operations after the finished record has been taken.

It will be understood that after pin 23 leaves the notch in the locking dog 24 this dog will be restored to its engaging position by means of a suitable restoring spring 39 which is connected to the tail 26 of the dog and to pin 30.

In order to print on the record card a number identifying the machine a slug 40 is provided which is fixed to a suitably fixed arm 41 and disposed adjacent the printing point on the type wheels 10 and 11. The interlocking mechanism herein described is particularly adapted for recorders of this class wherein an indeterminate time may elapse between the resetting of the wheels to zero and the taking of the new start record. Irrespective of the duration of this time the recorder wheels will be prevented from advancing until after the proper zero or start record has been taken. After such start record has been taken the various time wheels are advanced step by step by the coil spring 15 under the control of the escape-ment wheel 14. The ratchet wheel 13 through pawl 18 tends to drive the escape-ment wheel forward. Such movement is restrained by the scape arms 16 and each time these scape arms are operated by the magnet 17 the time wheels advance one step.

In order to provide for the replacement of different time intervals or value bands 10 or 11 I preferably provide the time wheels with brass bands 42 on their periphery having struck-up figures representing the type. These bands are removable from the wheels by means of a clamping block 43 shown in Fig. 1 and secured in clamping position by means of a screw 44.

Before an initial record is made it is presumed that the recorder has been reset

by rotating member 21. The operator places a card in the card receiver and depresses the handle 22. The hammer 28^a is operated to print a starting time record upon the inserted card. Depression of the printing handle 22 also releases dog 24 and releases the zero stop pin 23. Type wheels 10, 11 then move forward under the control of the magnet 17. As soon as these type wheels move forward a card abutment lever 33 rocks to the dotted line position (Fig. 3) so as to position a different portion of the record card at the printing point upon the next recording operation. Upon the following recording operation the card is reinserted in the card chute and the handle 22 is again actuated. This operation prints the finish time record showing the direct elapsed time upon the record card. After the finish record is taken an interlocking element 36 comes into operation to prevent further printing operations after the finish record has been taken. Following the taking of the finish or elapsed time record, the type wheels and pertinent parts must be reset by a manual rotation of member 21. When the type wheel is fully reset pin 23 will engage the notch in dog 24 which will snap forward under it. This dog will then prevent the advance of the type wheels until the taking of a new start record.

What I claim is—

1. A time recorder including in combination, a time-controlled type wheel, means for taking zero and elapsed time records from said wheel, means for resetting said wheel to zero and means for preventing the subsequent advance of the wheel until a new zero record has been taken.

2. A time recorder comprising in combination, a wheel carrying related time and value type time-controlled means for controlling the advancing of said wheel, means for taking a record of elapsed time and corresponding value from said wheel, means for resetting said wheel to zero, and means for preventing any advance of said wheel from zero until a start record has been taken.

3. A time recorder comprising a time-controlled type wheel, means for resetting said wheel to zero, a combined reset and zero stop element connected to said wheel to move in unison therewith, a dog cooperating with said stop element to limit the resetting movement of said wheel, and having provisions for also limiting subsequent advancing of said wheel, and means for disengaging said dog after a record has been taken from the wheel.

4. A time recorder including a time-controlled wheel, a stop pin moving in unison with said wheel, a plurality of members coacting with said stop pin, one member being a movable card abutment, and a second member constituting a reset to zero stop de-

vice, said last mentioned member having provisions for locking said wheel against advancing movement.

5. In a time recorder having a time-controlled type wheel, means for resetting the same to zero, means for limiting the resetting movement of said wheel, said last mentioned means also constituting a means for preventing a subsequent advance of said wheel.

6. A time recorder including in combination, a time-controlled wheel from which records may be taken, means for resetting said wheel to zero, means operable upon the

resetting of said wheel to zero for indefinite-¹⁵ ly preventing the advancing of said wheel until a record has been taken therefrom.

7. A time recorder comprising a time-controlled wheel from which records may be taken, means for resetting said wheel to ²⁰ zero and means for retaining said wheel in such zero position, and means controlled by the record taking means for rendering said last mentioned means ineffective whereby the time-controlled wheel may be advanced. ²⁵

In testimony whereof I hereto affix my signature.

CLAIR D. LAKE.
